SHADE ROLLER

Filed Oct. 4, 1929

INVENTOR.

Charles F. Schenck

UNITED STATES PATENT OFFICE

CHARLES F. SCHMELZ, OF BRIDGEPORT, CONNECTICUT, ASSIGNOR TO STAY-PUT SHADE ROLLER CORPORATION, OF BRIDGEPORT, CONNECTICUT, A CORPORATION OF CONNECTICUT

SHADE ROLLER

Application filed October 4, 1929. Serial No. 337,347.

This invention relates to shade rollers such as are generally used in connection with windows, and it has for its principal object the provision of a device which obviates many of the deficiencies and annoyances inherent in the shade rollers heretofore used.

Shade roller device in common use is provided with a torsional spring which is tensioned increasingly in proportion to the distance to which the shade is pulled down, and which serves to rewind the shade when the roller is released from its detaining members by jerking the shade. But, the shade roller, made in accordance with the present invention, has no such spring device. With it the shade may be pulled down smoothly, and its end will stay exactly where it is left when the pull is discontinued. The shade is raised by a separate cord wound on a spool which rotates with the roller, and it will remain exactly where it is when the pull on the cord is discontinued. Thus, shades at adjacent windows may be raised or lowered to bring the ends exactly in line with each other, as fastidious persons are wont to do, with ease, a thing notoriously difficult with spring-rewound shade devices.

A feature of this invention is the provision of means for frictionally holding the shade in any adjacent position by means which automatically becomes inoperative while the shade is being pulled up by the cord-operated rewinding device so as not to add any burden to the rewinding operation.

Another feature of this invention is the provision of a shade-rewinding device, all parts of which are mounted on the bracket for the shade roller, there being merely a clutch between the bracket-carried parts and the roller, so as to permit the economic manufacture of the device and easy installation; and another feature is the provision of a clutch between the bracket-carried parts and the shade roller which is of such construction as to support the shade roller on the bracket, although, in some forms of the invention, it is preferable to have, in addition, a trunnion pin on the roller fitting a socket on the bracket for the parts carried thereby.

And still another feature of this invention

is the provision of means for holding a shade-rewinding spool, which is mounted on the bracket, against rotating in a direction which would tend to cause the cord thereof to unwind from the spool when the shade and roller are removed from the bracket.

Other features and advantages will herein-after appear.

In the accompanying drawings, which illustrate the preferred embodiment of the invention—

Figure 1 is an enlarged side view of my improved shade roller partly in section and supported on a window casing.

Fig. 2 is a section on line 2 of Fig. 1.

Fig. 3 is a section on line 3 of Fig. 1.

Fig. 4 is a view of the bracket which carries the mechanism for operating the roller, and which is here shown as it appears when the roller has been removed therefrom.

Fig. 5 is an end view of the shade roller per se, as indicated by line 5 of Fig. 1.

Briefly stated, the shade roller comprises, in its general entity, three principal elements, viz: the roller per se, which carries the shade-fabric and is, as usual, attached thereto at one end with tacks or similar devices, and also a pair of brackets which support the opposite ends of the roller, respectively, and which are generally called the "roller hardware". Of the latter, one bracket supports the "live" end of the roller, that is to say: that end which is operated by the mechanism for rotating the roller either to raise or lower the shade, while the other end constitutes the support for the "dead" or idle end of the roller having no function other than removably carrying that roller-end and acting as a journal or bearing therefor.

Referring to the present invention, the roller 10 consists substantially of a cylindrical member which may be made of wood or metal as preferred, and which carries the shade 11, one end of which is secured to the roller in any suitable manner, and which may be rolled up on the same, or pulled down, as the case may be. On its dead end, the roller 10 is provided with a metallic ferrule 12 and a trunnion pin 13 which is adapted to be placed into a bracket 14 attached to the win-

dow-casing and having a slot or opening 15 to permit its ready insertion or removal.

The device illustrated in Fig. 1 is supported by the brackets located in the runways for the inner or lower sash of the window casing which latter has the usual parting strips 16 whereby the lower sash is guided in its vertical movement. The brackets may be attached to the window casing by suitable 10 screws (not shown) passing through apertures or perforations 17 provided for that purpose. It will, therefore, be understood, that the roller, as shown, is lying directly above and in the same vertical plane with 15 the lower sash and in the upper portion of the casing, so as not to interfere with the upward movement of the sash, which movement may be limited by projecting stops 18 formed by bending the metal plate of which the 20 bracket is made, as illustrated in Fig. 1.

The live or opposite end of the roller is indirectly supported by a bracket 20 which is secured to the opposite portion of the casing and which carries a mechanism whereby the 25 roller may be rotated positively in opposite directions to lower or raise the shade as required. This end of the roller is provided with a trunnion pin 21 centrally located on the roller end and passing through a central 30 perforation provided therefor in the ferrule 22 disposed on the roller end, as shown.

The pin 21 is provided with a shoulder or collar 23 for limiting its insertion into the roller and it also has a projecting trunnion-extension 24 provided with a conical end 25 to facilitate its entrance into a sleeve or bearing member 26, when the roller is to be placed into the brackets.

The sleeve or shell 26 is preferably in 40 screw-threaded engagement with a hub 27 which is formed by piercing and drawing the base plate of the bracket 21 into a condition substantially as shown in Fig. 1, this hub being an integral part of the plate, and possessing, therefore, great strength and rigidity. A slot 26' formed in the end of the shell 26 permits the use of a screw-driver for screwing the shell into or out of the hub 27.

Normally, free rotation of the roller is 50 resisted by a braking device which is primarily intended to counteract the weight of the down-hanging portion of the shade and the shade-stick 28 whereto a pulling-down cord is usually attached. This brake constitutes 55 in its preferred form a part of a spool comprising a guard or flange 30 which has a neck-portion 31 forming a drum on which the raising cord 32 (to be hereinafter referred to) will be wound-up when the shade is pulled down. The neck 31 of the flange 30 fits 60 tightly on the annular hub portion 32 of a companion flange 33 of the cord spool, whose periphery is cupped at 34 to receive a cam ring 35 rotatable therein and having cam 65 faces 36 respectively engaged by rollers or

disks 37 which are confined within the free space bounded by said cam faces 36 and the outer surface of the bracket hub 27 above mentioned. As a matter of fact, three of these disks 37 are preferably used, the entire 70 device constituting a roller clutch of well-known construction and operation, one of the disks being always in position to operate in checking the movement of the cam ring 35 in the direction of arrow A.

The flanges 30 and 33 are corotatively connected by prongs 30a of the flange 30, entering perforations 33a in the flange 33, where they may be spot-welded and the spool thus formed may be coupled to the roller 10 by ribs 37 formed by lancing and punching certain portions of the flange 30 in the manner illustrated in Figs. 1 and 4 of the drawing. These nibs 37 are adapted to enter suitable perforations 38 provided therefor in the ferrule 22 above described, eight perforations being illustrated, four of them being engaged at the same time by the set of four nibs 37, as will be readily understood. By virtue of this construction, the roller 10, when being placed 80 in position on the bracket, is capable of assuming eight different positions of engagement with the nibs 37, so that it requires only a maximum rotation of 45 degrees relative to the perforations 38, by the roller to establish connection between these two parts.

It will be understood that, when the roller 10 is rotated by pulling the shade down, both flanges 30 and 33 will move in the same direction and in unison with the roller. In order 100 to cause the cam ring 35 to move with the flange 33 during this corotation, means are provided for establishing a frictional driving connection between the cam ring 35 and the flange 33, this means consisting, in the preferred form thereof shown, of a spring disk or washer 40 having a central aperture 41 (see Fig. 1) for passing over the hub 27 of the base plate. This spring washer is forced against the left face of the cam-ring 35 (as 110 viewed in Fig. 1) by one or more adjusting shims or washers 42, it being evident that the more shims or washers 42 used, the greater will be the pressure exerted by the outer peripheral portions of the spring disks 40 115 against the outer face of the cam ring 35.

In order to resist this spring action, which naturally would tend to move the entire spool longitudinally toward the right of the hub 27, the sleeve 26 has a head flange 26a which is seated firmly against the outer end of the hub 27 and overlaps the cylindrical hub 32 of the flange 33, so that, therefore, the location of the spool in its entirety on the hub 27 will always be the same longitudinally thereof.

By referring to Fig. 2, it will be noted that the spring disk 40 is preferably made in the form of a spider having resilient arms, preferably six in number, three of which are locked with their outer ends pressing against the cam 120

ring 35 by the flange 34 being headed-over as shown at 43 (see Figs. 1 and 2), while the other three arms are slightly longer and rest in recesses or notches 44 provided for them in the flange 34, this construction being instrumental in causing the friction spider to move with the flange 30, so that when the cam ring 35 is stopped against rotation with the roller, both sides of the same are frictionally engaged, and the braking effect will, due to the friction established between these three parts, be doubled as compared with the effect which would exist if the spring spider 40 were free from its drive-connection with the flange 30. This means: that the pressure exerted against the sides of the cam ring may be correspondingly less, and the efficiency of the entire device as to braking effect will be considerably enhanced.

It is preferable that the friction required to hold the shade roller against rotation by the weight of the shade itself be proportionate to such weight which naturally depends upon the width of the shade, and also upon the maximum length of the shade which may be pulled down from the roller; but when once determined, it will remain constant, a feature which is not found in the devices used heretofore.

In Fig. 1, the shade is illustrated being rolled up high on the roller, while the spool cord is illustrated as being entirely unwound, and hanging loose, it being held in comparatively straight condition preferably by a small tassel 50 (see Fig. 2). When the shade is now pulled down, the cord will be wound up on the drum 31, and in the space between the flanges 30 and 33. Then, a pull on the cord will cause the spool to rotate in the direction of arrow B, therefore carrying the cam ring 35 along with it and consequently relieving the disks 37 (which jam the cam ring against rotation in the other direction) from all action, that is to say: they are simply carried around loose within the pockets 35a opening into the space in the cam ring, without producing any braking effect.

The cord 32 is attached to the spool by passing it through a perforation 51 provided for that purpose in the flange 30, and leaving the knotted end 52 of the cord on the outside of the flange, the construction herein illustrated bringing the initial convolution of the cord, as it is wound on the drum, into direct contact with the drum 31 and also closely against the flange 30, so that it will be wound on evenly and snugly, a feature which is very desirable and will be assisted by the weight of the tassel 50 above referred.

When the shade has been lowered or unrolled from the roller, it will naturally have the greatest weight, which, under ordinary conditions, will make it more difficult to pull the shade up, but, in view of the fact that when the shade is in lowered condition, the outer-

most convolution of the cord on the spool will be at its greatest distance from the center of its rotation, so that, therefore, the inherent leverage produced by such organization at that time will counteract the weight of the shade and a very slight pull on the cord will be sufficient to roll the shade up.

Furthermore, as the shade is being pulled up, its down-hanging length naturally becomes shorter and its weight becomes, therefore, gradually less. At the same time, the cord is correspondingly unwound from the spool and the point of pull approaches the center of the spool gradually and proportionately. In any event, the two factors are so proportioned as practically to equalize each other so that the actual resistance offered to the pull on the cord remains practically the same throughout.

As above referred to, the frictional resistance to the down-pull of the shade is, by means of the shims 42, gaged to offset the weight of downhanging or unrolled length of the shade, that is to say: it must be sufficient to hold the roller against being rotated by the weight of the shade, so that it must always require a pull to lower it. Now, inasmuch as the frictional resistance remains always the same, the strength of pull required to pull the shade down will vary proportionately to the weight-pull exerted by the down-hanging length of the shade, this weight-pull naturally increasing as the shade is being pulled down. This, then, means: that the required hand-pull becomes gradually less, because it is assisted by the weight of the shade.

The brake mechanism above described is designed to produce the necessary resistance to the pull of the weight of the shade, but, as stated, it is effective only when the roller tends to rotate in the direction of arrow A (see Fig. 3).

Sometimes it may be desirable or necessary to remove the roller from its supporting brackets, as for instance when the windows are to be washed, or the shades are to be cleaned, etc. In that case, the spool would be free to be rotated in the direction of arrow B by the weight of the cord and its tassel, and thus disarrange the proper cord-length primarily determined upon. The present invention has, therefore, for another of its aims: to provide means for counteracting this tendency without, however, adding materially to the pull on the cord necessary to raise the shade. Practice has demonstrated that this "minor" friction is established by the contact of frictional engagement between the spool and the supporting bracket, as follows:

As above stated, the spring washer or spider 40 which rests with its central portion against the shims 42, exerts a pushing force against the cam ring 35 and, consequently, against the flange 33, therefore crowding the outer

end of the hub 32 against the head-flange 26a, and thus creating a frictional contact between these parts. In addition to this, frictional contact exists, indirectly, between the spider 5 (which is corotatively connected with the spool flange 32) and the face of the stationary support-bracket 20, both frictional engagements being located near the center of support and therefore having only a minor efficiency as compared with the major frictional efficiency exercised upon the peripheral portions of the spider 40 and the flange 32 upon the sides of the cam ring 35, the hub-friction being sufficient to prevent the spool from 15 being pulled around by the cord and its weight-tassel 50.

In devices of this kind, the cost of manufacture which comprises the cost of the raw material, the labor required to bring the 20 raw material into finished condition, and the assembling of the finished parts into unity, must be taken into consideration, in order to bring the cost of the entire proposition down to a minimum, and it is for this reason that 25 the present invention embodies and provides parts such as can be very accurately made by the stamping process. Such parts are naturally made with tools which permit production in large quantities and the parts come 30 from the tools requiring practically no finishing. It is for this reason that the entire working unit of the present invention, including the bracket, can be readily assembled without the requirement of adjusting any of the parts 35 relative to each other, except as hereinbefore stated when referring to the shims 42.

Variations and modifications may be made within the scope of this invention and portions of the improvements may be used without others.

Having thus described the invention, what is claimed as new and for which it is desired to obtain Letters-Patent, is:—

1. In a device of the character described 43 comprising a shade roller having a trunnion, a shade-raising unit mounted on a support for rotatably supporting and operating said roller and having a socket for the roller trunnion, and cooperating clutch means on the 55 roller and unit for rotatably and detachably connecting the roller and unit.

2. In a device of the character described 58 having a shade roller, a shade-raising unit mounted on a support for detachably supporting and operating said roller, said unit including a spool upon which a cord is wound so that the unwinding of the cord causes the shade to be raised by being wound upon the roller.

3. In a device of the character described 65 having a shade roller, a shade-raising unit mounted on a support for detachably supporting and operating said roller and including a spool upon which a cord is wound so that the unwinding of the cord causes the shade to

be raised by being wound upon the roller, and a clutch between said cord spool and the shade roller for causing them to rotate in unison in both directions.

4. In a device of the character described 70 having a shade roller, a shade-raising unit mounted on a support for detachably supporting and operating said roller and including a spool upon which a cord is wound so that the unwinding of the cord causes the shade 75 to be raised by being wound upon the roller, a clutch between said spool and the roller for causing the spool and roller to rotate in unison in both directions, and means for frictionally holding the cord spool and shade 80 roller against a tendency to rotate in a direction which causes lowering of the shade.

5. In a device of the character described 85 having a shade roller, a shade-raising unit mounted on a support for detachably supporting and operating said roller and including a spool upon which a cord is wound so that the unwinding of the cord causes the shade to be wound upon the roller, a clutch between said cord spool and the shade roller 90 for causing them to rotate in unison in both directions, and means for frictionally holding the spool against a tendency to rotate in either direction.

6. In a device of the character described 95 having a shade roller, a shade-raising unit mounted on a support for detachably supporting and operating said roller and including a spool upon which a cord is wound so that the unwinding of the cord causes the shade 100 to be raised by being wound upon the roller, means for detachably coupling said roller and spool for co-rotation, and means for frictionally holding the cord spool and shade roller against a tendency to rotate in 105 a direction which causes lowering of the shade.

7. In a device of the character described 110 having a shade roller, a shade-raising unit including a spool upon which a cord is wound so that the unwinding of the cord causes the shade to be raised by being wound upon the roller, a brake member normally rotatable with the spool, a fixed support, and a clutch between the brake device and the fixed support adapted to automatically lock the brake member against turning when the spool rotates in a direction which causes the shade to be unwound from said roller.

8. In a device of the character described 120 having a shade roller, a shade-raising unit including a spool upon which a cord is wound so that the unwinding of the cord causes the shade to be raised by being wound upon the roller, said spool having a cupped flange, a 125 brake device rotatably mounted in the cupped portion of the flange, a stationary support having a boss, and clutch members located in the cupped portion of said flange and between cam-shaped surfaces on the brake mem- 130

ber and the boss on said stationary support to automatically lock the brake device against turning when the spool rotates in a direction which causes the shade to be unwound from said roller.

6 9. In a device of the character described having a shade roller, a shade-raising unit including a spool upon which a cord is wound so that the unwinding of the cord causes the 10 shade to be raised by being wound upon the roller, a brake device rotatable with the spool, means for holding the brake device against rotation, friction-producing means between the 15 brake device and the spool, and means for varying the pressure of the friction-producing means.

10 10. In a device of the character described having a shade roller, a shade-raising unit including a spool upon which a cord is wound 20 so that the unwinding of the cord causes the shade to be raised by being wound upon the roller, said spool having a flange, a brake device rotatable with the spool, a fixed support, a clutch for locking said device against 25 rotation in the shade-lowering direction, and disposed between the brake device and the fixed support, and a spring carried by the flange and adapted to yieldingly urge the brake device against the flange on the spool.

20 11. In a device of the character described having a shade roller, a shade-raising unit including a spool upon which a cord is wound 25 so that the unwinding of the cord causes the shade to be raised by being wound upon the roller, said spool having a flange, a brake device rotatable with the spool, a fixed support, a clutch between the brake device and the fixed support, a spring carried by the flange and adapted to yieldingly urge the 30 brake device against the flange on the spool, and shims between the spring and fixed support for determining the pressure of said spring against the brake device and hence the friction between the brake device and the 35 flange on the spool.

Signed at Bridgeport, in the county of Fairfield and State of Connecticut, this 3 day of October, 1929.

CHARLES F. SCHMELZ.
